UNITED STATES PATENT OFFICE.

WILLIAM MILLER, OF AMESBURY, MASSACHUSETTS, ASSIGNOR TO AMESBURY
BRASS & FOUNDRY COMPANY, OF AMESBURY, MASSACHUSETTS, A CORPORA-
TION OF MASSACHUSETTS.

WINDOW-FASTENER.

1,387,860.

Specification of Letters Patent. Patented Aug. 16, 1921.

Application filed June 2, 1920. Serial No. 385,881.

To all whom it may concern:

Be it known that I, WILLIAM MILLER, a citizen of the United States, residing at Amesbury, county of Essex, State of Massachusetts, have invented a certain new and useful Improvement in Window-Fasteners, of which the following is a specification, reference being had therein to the accompanying drawings.

10 The invention relates to a new and improved type of window fastener and anti-rattling device, which is particularly adapted for use on the windows of vehicles.

15 The object of the invention is to provide a device which will secure the sash in any desired position and at the same time prevent it from rattling. Another object of the device is to provide a handle by which the sash may be lifted.

20 The invention will be fully understood when taken in connection with the accompanying drawings, and the novel features thereof will be pointed out and clearly defined in the claims at the close of this specification.

25 In the drawings, Figure 1 is a view in elevation of a vehicle door equipped with a device embodying the invention.

Fig. 2 is an enlarged sectional view taken 30 on line 2—2 of Fig. 1.

Fig. 3 is an enlarged sectional view taken on line 3—3 of Fig. 1.

Fig. 4 is a detail of the latch.

35 Referring now to the drawings, I have shown my improved lock applied to a window in a door of a motor vehicle, as it is particularly adapted for this use.

40 At 11 is indicated the door which is provided with a sash 4 equipped with a device embodying the invention. The sash is slidably mounted in the window frame 13 which is provided at each side thereof with vertical channel members 5. The channel members 5 are covered with a resilient material preferably felt, as shown at 14 in Fig. 3.

45 A notched bar 6 secured to the garnish rail 13 of the window frame by screws 15 cooperates with a latch 16 pivotally mounted on the sash 4 to form the fastener and anti-rattling device embodying the invention.

50 The latch 16 is mounted on the sash in the following manner:—Attached to the glass 17 at each side thereof are binding members 8 and 9, which are U-shaped in cross section

and which extend the full height of the glass. The binding member 8 is provided with a flange *a* as shown in Fig. 3 to which is secured a bracket 18 which forms a support for the latch 16 of the window fastener.

55 The bracket 18 is secured to the flange by rivets 19 and has two laterally extending ears 20 adapted to receive the pivot pin 21 on which the latch 16 is mounted.

60 Surrounding the pivot pin 21 is a coiled spring 22, one end of which engages the bracket rigidly secured to the sash, and the other end of which bears on the latch to normally hold it in engagement with one of the notches 7 in the bar 6.

65 The latch is provided with a handle *b* on one side of its pivot, which may be used as a knob to move the sash to any desired position, and at the side adjacent the window frame is formed with a tooth *c* which engages the notched bar 6 attached to the garnish 75 rail of the window or door frame.

70 As will be seen by reference to Fig. 4, the tooth *c* of the latch is formed in the shape of a wedge, and the notches 7 in the bar 6 are given a corresponding shape (see Fig. 2). 80 This construction provides means whereby rattling produced by tendency to an up and down movement is eliminated.

75 It will also be seen that the action of the latch spring fastens the sash to the window frame and the pressure of the spring prevents vibration of the sash in and out relative to the window frame.

85 The construction is therefore such that the window sash is held from movement in and out and also vertically, so that a single device of very inexpensive construction holds the window from all movement, and forms a fastener as well.

90 I have shown but a single device embodying my invention applied to the window illustrated in the drawings but in the case of a very wide sash it may be advisable to use one at each side thereof.

95 What I claim is:—

100 1. In a device of the character described and in combination with a window frame having a notched bar secured thereto, a window sash, a latch pivotally mounted on the said sash, the axis of the pivot being parallel with the notched bar and a spring acting on the said latch to cause the point of the latch to engage a notch in the said bar 105

and by its reaction to restrain the sash from movement in and out relatively to the frame.

2. In a device of the character described and in combination with a window frame 5 having a notched bar secured thereto, a window sash, felt interposed between the sash and the frame, a latch pivotally mounted on the said sash, the axis of the pivot being parallel with the notched bar and a spring 10 acting on the said latch to cause the point of the latch to engage a notch in the said bar and by its reaction to restrain the sash from movement in and out relatively to the frame.
- 15 3. In a device of the character described, a window frame, a sash having a binder member secured to the glass, said binder member having on one side a lug bent up therefrom, a latch secured to the said lug, 20 a notched bar on the frame, and a spring to cause the point of the latch to engage one of the notches in the said bar.
4. In a device of the character described, a window frame, a sash, a latch pivotally 25 mounted on the sash and having a wedge-shaped tooth with two inclined converging faces, a notched bar secured to the window frame, the notches in said bar corresponding in shape to the tooth on the latch to co- 30 operate therewith and restrain the sash from movement up and down relatively to the window frame.
5. In a device of the character described and in combination with a window frame 35 having a channel for a window sash, a felt
- facing for the wall of the channel, a sash 40 slideable in said channel, a notched bar secured to the window frame, a latch pivotally mounted on said sash, and a spring which acts on said latch to normally cause the latch to engage with a notch in said bar, and to cause the sash to have an elastic pressure against the felt facing of the channel.
6. In a device of the character described, a window frame, a sash, a latch pivotally 45 mounted on the sash and having a wedge-shaped tooth with two converging faces at equal angles of inclination, a notched bar secured to the window frame, the notches in said bar having two converging faces corresponding with the converging faces of the tooth, and a spring which causes the tooth of the latch to engage with one of the notches in a wedging manner.
7. In a device of the character described, 50 a window frame, a sash, a latch pivotally mounted on the sash and having a wedge-shaped tooth with two converging faces at equal angles of inclination, a notched bar secured to the window frame, the notches 55 in said bar having two converging faces corresponding with the converging faces of the tooth, and a spring which causes the tooth of the latch to engage with one of the notches in a wedging manner, the converging faces 60 of the notches and of the tooth being converged when viewed in a horizontal direction, and the sash being movable vertically.

In testimony whereof I affix my signature.
WILLIAM MILLER.
